UNITED STATES PATENT OFFICE.

BARNES NEVILLE WALLIS, OF WESTMINSTER, LONDON, ENGLAND, ASSIGNOR TO AIRSHIP GUARANTEE COMPANY, LIMITED, OF WESTMINSTER, ENGLAND.

LIGHTER-THAN-AIR AIRCRAFT.

Application filed December 16, 1925, Serial No. 75,884, and in Great Britain January 21, 1925.

This invention relates to lighter-than-air aircraft.

At the present time the outer cover or envelope of an airship is usually maintained taut by the combined use of dope and a system of lacing. Apart from the fact that it is impossible by this method to prevent a certain degree of sagging at any time, flapping or increased sagging of the outer cover occurs, during continued use, owing to deterioration in the dope or to slackening of the lacing, thereby distorting the contour or outer surface of the airship and reducing its speed and sensitiveness to control.

According to the present invention the outer cover of an airship is maintained taut by inflating or distending the same. This result may be obtained by placing the space between the outer cover and the gas bags in communication with the atmosphere by means of air scoops or openings, usually located in the neighbourhood of the nose of the airship, so that the outer cover is distended by air pressure. Alternatively, a mechanical blowing engine may be developed for the purpose, or else the exhaust gases from the engines, either before or after they have been deprived of their water content, may be used, or a combination of any or all of these methods may be employed. When the airship is in motion and even at moderate speeds the pressure of the air at the nose of the airship will be adequate to secure the desired result, and, when the ship is moored, the cover will also remain tight if there is any wind. If, however, there is not sufficient wind to keep the cover taut and should it be desired to keep it taut or prevent sagging when the ship is moored, a mechanical blowing engine may be provided on the airship, or on, or adjacent to, the mooring mast for use under these conditions. Alternatively, and in cases where provision is made for using the exhaust gases of the engines the same result may be attained when the ship is moored either by running the engines slowly or faster with the clutches out. The aforesaid method or methods of maintaining the outer cover taut may also be employed in conjunction with any of the usual methods by which attempts have been made in the past to maintain the outer cover taut, e. g., lacing or the use of dopes. If desired, the space

may be divided into independent sections each of which is placed in communication with the atmosphere by an air scoop or aperture at the nose of the airship. In the case of a rigid airship of polygonal cross section, the outer cover need only be attached along the longitudinal frames. As there will be a slight leakage of the high pressure air through various openings in the outer cover to the atmosphere which will cause a certain amount of air to circulate in the space between the gas bags and the outer cover the use of the present invention also has the advantage that it cools the gas bags and ventilates the space between the gas bags and the outer cover, so that the usual ventilators or air scoops can be dispensed with. The usual air scoops are in themselves objectionable, as they form protuberances which interfere with the streamline flow around and along the hull or body, and, as the present invention enables these protuberances to be dispensed with, the speed of the airship and its sensitiveness to control is increased.

Furthermore, although attempts have been made to construct an airship having one of the most approved streamline forms, the advantages derived from the adoption of such streamline form are detracted from owing to sagging of the outer cover which results from the usual methods of maintaining the outer cover taut. On the other hand, the present method of maintaining the outer cover taut also has the advantage that it allows an airship to be constructed having the most approved streamline form, and to allow such streamline form to be maintained at all times when the airship is in flight. For example, it is known that a body having a ratio of overall length to maximum diameter of $4\frac{1}{2}$ or 5 to 1 will offer a very low resistance to propulsion through the air provided the following proportions are generally maintained:— (a) The head or front portion is approximately two diameters long, at which distance from the nose the maximum diameter occurs, that such head or front portion should consist of a semi-prolate ellipsoid, that is to say, the solid formed by the rotation of a semi-ellipse about its major axis, and that (b) the tail or after portion should be approximately $2\frac{1}{2}$ or 3 diameters long measured from the place at which it joins the head portion. By adopting the present method of maintaining

- the outer cover taut the aforesaid streamline shape can be produced and maintained during flight by connecting the outer cover to fixed portions of the airship, such as the longitudinal frames, such connecting means being of such a length or character, and being so arranged that under the influence of the air pressure in the space between the gas bags and the outer cover the latter will take up and maintain during flight the desired streamline shape.
- 5
- 10

The aforesaid method of maintaining the outer cover of an airship taut can advantageously be used in combination with the invention described in our co-pending application No. 760 of 1925, where the front part of the airship up to the maximum diameter thereof is kept free or substantially free of external protuberances.

20

The invention is illustrated diagrammatically in the accompanying drawing which shows an airship constructed according to the present invention and in which —

A is the air space between the outer cover B and the gas bags C. D is an air inlet situated at the extreme nose of the airship where there exists a state of high pressure and zero velocity relatively to the tail of the airship where there exists high relative velocity and zero or negative pressure. Instead of a single opening as shown two or more openings may be provided at the extreme nose of the airship so as to place the space A between the outer cover B and the gas bags C in communication with the atmosphere. In the example illustrated in the drawing a number of separate air compartments are provided along the length of the

ship and to this end a main air conduit E is provided which is in communication with the air inlet D, said conduit being provided with branch pipes F fitted with valves F' for the purpose of admitting air from the main air conduit E to the separate compartments G, G, along the length of the ship, the compartments G being formed by dividing up the air space A at suitable distances apart into separate chambers by means of fabric bulkheads H, H.

What I claim and desire to secure by Letters Patent of the United States is:—

1. A method of maintaining taut the outer cover of an airship which consists in providing a space completely surrounding the gas bags and located between the outer cover and the gas bags, said space being placed in communication with the atmosphere by air admission means situated at the extreme nose of the airship in the region of maximum pressure and zero velocity so that the outer cover is distended by the air pressure at the nose of the ship.

2. A method of maintaining taut the outer cover of an airship which consists in providing a space completely surrounding the gas bags and located between the outer cover and the gas bags, said space being divided into independent sections, each of which is placed in communication with the atmosphere by air admission means situated at the extreme nose of the airship in the region of maximum pressure and zero velocity so that the outer cover is distended by the air pressure at the nose of the ship.

BARNES NEVILLE WALLIS.
